US00D582017S

(12) United States Design Patent
Yuan

(10) Patent No.: US D582,017 S
(45) Date of Patent: * Dec. 2, 2008

(54) FAUCET SPOUT

(76) Inventor: Ai Hui Yuan, 2431 NW. Irving #24,
Portland, OR (US) 97210

() Term: 14 Years

(21) Appl. No.: 29/289,273

(22) Filed: Jul. 13, 2007

(51) LOC (8) Cl. 23-01

(52) U.S. Cl. D23/255

(58) Field of Classification Search D23/255-257,
D23/238-243; 4/675-678; 137/801

See application file for complete search history.

Primary Examiner—Robert A Delehanty

(57) CLAIM

The ornamental design for a faucet spout, as shown and described.

DESCRIPTION

FIG. 1 is a perspective view thereof;

FIG. 2 is a front elevational view thereof;

FIG. 3 is a right side view, the left being a mirror image; and,

FIG. 4 is a top plan view.

The broken line showing of environmental structure is for illustrative purposes only and forms no part of the claimed design.

1 Claim, 4 Drawing Sheets
